UNITED STATES PATENT OFFICE.

EMIL GMINDER, OF REUTLINGEN, GERMANY.

ELIMINATION OF FIBROUS WASTE FROM MACHINES.

Application filed September 18, 1926, Serial No. 135,735, and in Germany October 31, 1925.

In many machines for the production of fibers and fibrous material, and for the weaving or other treatment of such fibers or fibrous material, the efficiency of the moving parts is often impaired by flying waste which frequently accumulates on the moving parts in the form of flocks or flocculent masses which have heretofore been eliminated only with difficulty and with considerable loss of time.

Such flying waste accumulates particularly on the warp thread guards for looms, and enters the apertures of the stop-motion so as to prevent or interfere with the dropping movement of the individual stop motions. Flying waste also accumulates at the cross rods in the space between the lost motion rod and the crossing of the warp, and which is utilized for the purpose of effecting a sub-division of the number of threads lying one next to the other, to one half their number, by dividing the warp threads when the warp is very close together.

In carrying out my invention I eliminate such flying waste in a very simple and effective manner, by means of a tool which is adapted to be rapidly rotated, and which may be brought to a position adjacent to the front or the end of the collected fibrous material. The tool is so constructed that by its rotation in engagement with certain of the fibers, it will twist them together into a sort of roving and draw them from the machine.

If for instance one desires to clean the stop-motion, he can remove the flying waste from a group of the parts at the same time. The twisting process will continue within the group from the side at which it begins, to the far-side. The roving or twisted mass may then be easily extracted. The flying waste collected in such rovings may be reused.

In the accompanying drawing I have illustrated by way of example one apparatus embodying my invention, and which may be employed in carrying out my improved process. In these drawings:

Fig. 1 is a side elevation of a group of warp thread guards, and

Fig. 2 is a side view thereof.

In the construction illustrated there are a plurality of stop-motions *p*, each of which has an upper aperture *o* by means of which it is suspended, and also has a lower aperture or mold *l* through which extends the guiding rail *f*. These are standard parts of a loom. During the operation the waste material *v* collects in the mold *l*, and prevents or interferes with the dropping movement of the stop motion, and often prevents the proper operation of the device. This waste material extends through the apertures of all of the parts *p* above the rail *f*.

In order to eliminate this waste material in the course of the operation I provide a tool *k* which may be a hook or a clamp of pincher-like construction. This is connected to a shaft *w* which is preferably flexible. The tool *k* is brought into engagement with one end of the row or flock of waste fibers, and may be secured to some of them if desired. The rotation of the tool causes the fibers to twist together and become interconnected in a roving, so that when the roving is formed it may be pulled from one end, and all of the waste material removed from all of the stop-motions *p*. The work can be done very quickly and in some cases it is not necessary to interrupt the operation of the machine. All that is necessary is to drive the flexible shaft from any suitable source of power, as for instance a small electric motor, and to engage the tool with the end of the elongated mass of fibrous material. If desired the shaft may be driven by a portable motor, so that the workmen may carry the motor and the shaft and go from one machine to another in cleaning them.

Having thus described my invention, what I claim as new and desire to secure by Letters Patent is:

1. An apparatus for the elimination of fibrous flying waste from machinery, which includes a tool adapted to engage with the waste, and means for rotating the tool to form the waste into a roving.

2. A process for the elimination of fibrous flying waste from machinery, which consists in engaging the waste by a rotatable tool and thereby forming the fibers of the waste into

a connected roving which may be readily withdrawn from the machine.

3. A process for the elimination of fibrous flying waste from machinery, which consists in twisting the material into a roving and then removing the roving.

4. An apparatus for the removing of

fibrous waste from looms, including a flexible shaft and a tool connected thereto and driven thereby, for engaging the waste and twisting the fibers thereof together. 10

Signed at Stuttgart, Germany, this 3rd day of September, 1926.

EMIL GMINDER.
